CHARLES OGBURN HARPER, OF OMAHA, NEBRASKA.

ADJUSTABLE CURVE-RULER.

950,285.

Specification of Letters Patent. Patented Feb. 22, 1910.

Application filed May 3, 1909. Serial No. 493,628.

To all whom it may concern:

Be it known that I, CHARLES OGBURN HARPER, a citizen of the United States, and a resident of Omaha, in the county of Douglas and State of Nebraska, have invented a new and Improved Adjustable Curve-Ruler, of which the following is a full, clear, and exact description.

The invention relates to a curve ruler by which both regular and irregular curves may be made, and consists of an abscissa ruler or straight edge, a spring ruler, and ordinate rulers adjustable laterally and longitudinally of the abscissa ruler and arranged at the opposite end portions and at an intermediate point of the spring ruler, and the outer or end ordinate rulers having pivotal portions connecting them to and adjustable along the length of the spring ruler.

Reference is to be had to the accompanying drawings forming a part of this specification, in which similar characters of reference indicate corresponding parts in all the views.

Figure 1 is a perspective view of my improved adjustable curve ruler, showing the same adjusted to form an irregular curve; Fig. 2 is a perspective view of one of the slides carried by the abscissa ruler or straight edge, and by which this ruler and one of the ordinate rulers are adjustably connected; Fig. 3 is a fragmentary edge view of the spring ruler, showing the connection of one of the end ordinate rulers thereto; Fig. 4 is a side view of the construction shown in Fig. 3; Fig. 5 is a section through the connection between the spring ruler and the intermediate or central ordinate ruler; and Fig. 6 is a plan of the construction shown in Fig. 5.

An abscissa ruler or straight edge 10, a spring ruler 11 and ordinate rulers 12, 12, and 13, comprise the principal features of the appliance. The ordinate rulers 12, 12 are carried on the end portions of the abscissa ruler, and the ordinate ruler 13 is carried on the abscissa ruler between the rulers 12, 12, the connection between each ordinate ruler and the abscissa ruler being effected by a slide block 14, as shown in detail in Fig. 2, the block having slots 15 and 16 arranged at right-angles to each other one above the other and provided with threaded openings in the top to receive binding screws 17 and 18. The slots 15 and 16 of the blocks are of such size to respectively slidably fit the

abscissa ruler and ordinate ruler, these rulers being respectively secured in any desired position of adjustment by the screws 17 and 18.

The plane of the spring ruler 11 extends at right-angles to the planes of the other rulers and it is constructed with longitudinal slots 19 arranged at opposite sides of the center. In each of these slots is slidably a screw 20 having an angular portion adjacent to the head to prevent it from turning, and provided with a thumb-nut 21 at the outside. Each screw 20 passes through a bracket 22 having an inwardly-inclining arm arranged at approximately right-angles to that portion of the bracket through which the screw 20 passes, and provided with an upwardly-projecting stud 23 which passes through the apertured end of the adjacent ordinate ruler, and is provided with a thumb-nut 24 to bind this ruler and the bracket together. This manner of connecting the outer or end ordinate ruler to the spring ruler admits of the brackets 22 occupying any position on the spring ruler within the limits of their adjustment and making any required angle with the ordinate rulers, as is obviously necessary in adjusting the latter on the abscissa ruler. The center of the spring ruler is fixed to the outer end of the intermediate ordinate ruler 13 by a screw 25, which, as shown in Figs. 5 and 6, is threaded into a metal end-piece 26 riveted or otherwise secured to this ruler and of reduced width at its extremity in order that it will not present any substantial interference with the drawing of the curve from the outside of the spring gage.

In adjusting the instrument to make any regular curve, such as a semi-ellipse, the 95 ordinate ruler 13 is moved to the center and drawn close to the abscissa ruler and secured against both lateral and longitudinal movement by tightening the screws 17 and 18. The end ordinate rulers are then moved at 100 equal distances from the intermediate ordinate ruler, which may be determined by the graduations on the abscissa ruler. In this position further lateral movement of the ordinate rulers 12 is prevented by tightening 105 the screws 17, after which each of these rulers is moved outwardly a distance necessary to give the desired curve, when the screws 18, which hold them in place, are tightened 110 and the thumb-nuts 21 and 24, which during 115

the lateral movement of the end ordinate rulers are loosened, are then tightened. With all of the thumb-screws tightened, the spring ruler is comparatively rigid and is in readiness for the drafting of the curve required. By the adjustment of the ordinate rulers 12, substantially any regular or irregular curve may be obtained, and the size of the curve may be varied by substituting for the spring ruler 11, other like rulers of different length.

10 Having thus described my invention, I claim as new and desire to secure by Letters Patent:

1. The combination of an abscissa ruler, a 15 spring ruler, ordinate rulers carried by the abscissa ruler, longitudinally and laterally adjustable thereon, and brackets slideable along the length of the spring ruler and each having a pivotal connection with one of 20 the ordinate rulers.

2. The combination of an abscissa ruler, blocks slideable on the abscissa ruler, ordinate rulers slidably supported on the blocks, a longitudinally-slotted spring ruler, brackets 25 pivotally connected to the ordinate rulers, and binding screws adjustably con-

nected the brackets to the spring ruler through the slots.

3. The combination of an abscissa ruler, ordinate rulers adjustable laterally and longitudinally on the abscissa ruler, a spring ruler, means securing the spring ruler at an intermediate point to one of the ordinate rulers, and means adjustably connecting the end portions of the spring ruler to the other 35 ordinate rulers.

4. The combination of an abscissa ruler, blocks slideable on the abscissa ruler, a spring ruler, and ordinate rulers slideable in the blocks, with one of the ordinate rulers connected to the spring ruler intermediate its length and the other ordinate rulers each having a sliding connection with an end portion of the spring ruler.

40 In testimony whereof I have signed my name to this specification in the presence of 45 two subscribing witnesses.

CHARLES OGBURN HARPER.
